ATTORNEY

UNITED STATES PATENT OFFICE.

JOHANNES DINGEDAHL, OF HAMBURG, GERMANY.

ADVERTISING DEVICE.

Application filed March 20, 1923. Serial No. 626,330.

To all whom it may concern:

Be it known that I, JOHANNES DINGEDAHL, a citizen of Germany, residing at Hamburg, Germany, have invented certain new and 5 useful Improvements in Advertising Devices, of which the following is a specification.

This invention relates to display or advertising devices and in particular to signs, 10 the characters or figures of display being capable of constant change whereby a plurality of lines of writing or pictures or data can be changed simultaneously.

An object of the invention is to provide 15 a means whereby the displayed advertising signs will be used over again indefinitely and automatically without any attention on the part of the person using the device.

A further object is to provide independent sign members or plates which are brought to position singly and with a minimum of effort on the part of the actuating mechanism.

Referring to the accompanying drawings, 25 wherein one embodiment of my invention is illustrated:—

Fig. 1 is a face view of a sign board or box which is provided with openings through which the signs are displayed;

Fig. 2 is a side elevation in section taken on line 22 of Fig. 1 showing the operating mechanism in the interior of the device;

Fig. 3 is a side elevation similar to Fig. 2, the mechanism being shown in sign changing position; and

Fig. 4 is a rear elevation of my improved device showing the location of the various parts of the operating mechanism.

Referring to the drawings in detail, 40 wherein a casing is shown (a) denotes the front thereof which is provided with a series of aligned openings (b) disposed in rows to form sights through which may be seen suitable words or pictures used in advertising. 45 The casing is divided into compartments by the vertical walls (c) which are disposed between the openings (b), each of the vertical compartments containing the necessary mechanism to display and change the sign placards operating before the openings (b) of that particular compartment. Through 50 the bottom of the casing extends a shaft (d) which is rotated in alternate direction by any suitable means not shown such as a motor and alternating clutch.

Extending substantially the length of the compartments and on both sides thereof are disposed guide rails, the front one (e) and the rear one (f), upon the former of which is slidably mounted the spaced hooks (g) 60 and on the latter of which is also slidably mounted the spaced hooks (h).

The hooks (g) which may be termed the displacing hooks are connected by the hook connectors (i) and the rear hooks (h) or 65 replacing hooks are connected by the connectors (j). These connectors act as spacers and keep the hooks a given distance apart in their sliding movements on the rails.

The lower hooks (h) and (g) are connect- 70 ed by sprocket or like chains (m) which pass over the sprocket wheels (n) which are fixed to the shaft (d) which passes through the compartments, and also over idlers (o). The upper hooks (h) and (g) are also connect- 75 ed by cables (k) which pass over the rollers (l) in the top of the compartment, it being understood that there are two sets of hooks and their allied parts, one on each side of each compartment. 80

On the compartment walls there are disposed placard holding rails, the rails (p') sloping forwardly and ending adjacent the upper edge of the display openings (b), and the rails (p) sloping rearwardly and being 85 located adjacent the lower edge of the display openings (b). The rails (p) and (p') are provided with hooked or upturned ends (q), respectively on their forward and rear ends for a purpose later to be disclosed. 90

The placards (r) on which may be printed letters as shown in Fig. 1 or pictures or any suitable marking, are, we will say for illustration, supported one behind the other on the rails (p), the placards (r) 95 having at their upper opposite corners rail engaging studs (s) which are hooked at their outer ends downwardly to prevent sidewise movement of the placards. These studs rest on the tops of rails (p) and slide 100 thereon. The forward placards on rail (p) are in display position, see Fig. 2, and when the hooks (g) move upwardly they engage the studs (s) and carry the placards up off the rails. The hooks slope forwardly and the hooked ends (q) of the rails (p') are so located that the inner ends of the hooks (g) just engage the studs (s) of the forward placard (r) and when the studs clear the hooked ends (q) they slide down the 110

hooks and when the latter have a reverse movement the studs (s) will pass the rails (p') and allow the placards to be carried down until their lower edges rest in the 5 open backed receptacles (t), see Figs. 2 and 3, at which time they will fall backward upon a further downward movement of the hooks (g), the studs (s) at this time coming to rest against the rear hooked portions of the rearwardly sloping rails (p). The receptacles (t) are open at the back and are provided with inclined bottoms (y), so that the placards when placed therein will fall back through the rear openings and 15 their upper ends will rest on the rear of the rails (p). The receptacles are disposed at the proper distance below the forward edge of the rails (p) so that when the placards (r) touch the bottom thereof, the hooks 20 (g) upon a further downward movement will disengage the said placards and allow the same to fall rearwardly against the bottom (y) of the receptacle so that their studs (s) engage the rearmost portion of the 25 rails (p) at which point they will be in position to be successively engaged by the hooks (h) to be subsequently redisplayed. It will be seen therefore that the inclined bottom of the receptacles supports the placards on the rails (p) in position to be engaged by the hooks (h).

When the hooks (g) are moving down the hooks (h) in the rear are moving up, so it follows that they engage the rear or nearest placard studs (s) on the rails (p) and carry the placard up. The hooks (h) are also forwardly sloping and the studs (s) are engaged so as to remove only one placard which is then carried up on the hooks (h) until the studs are engaged and pushed back on the hooks by the curved rear ends of the rails (p') to pass the same after which the studs (s) slide forward on the hooks (h) and upon a downward or reverse movement of the same the studs are engaged by the rails and the placard (r) suspended thereby in position to slide down on the rails (p') until all the placards before it are used, at which time it again 50 appears in the opening for display. This action of course is continuous and takes place simultaneously in each compartment so that all lines of writing or other matter are changed simultaneously and a complete different presentation is made at the 55 openings. It is of course understood that the upper end studs of the placards resting on rails (p) move rearwardly by gravity as do the placards in position for display, 60 so that in any complete movement of the

hooks, placards are always being carried up and down, for replenishment and display.

It is to be understood that one line of writing may be used or that a plurality and that any indicia may be put on the placards, and that the rails may be of a length to accommodate any number of placards or articles so that the device may be used for a long time before repetition begins.

Having described my invention what I claim is:

1. A display device comprising a frame, a movable member, a holder, a placard on said holder in position for display, means on said movable member for removing said placard from display position, a receptacle for receiving said placard after it has been so removed, means for returning the placard to the said holder whereby it will be subsequently redisplayed, and an inclined bottom in said receptacle whereby the placard will be permitted to assume a position in the path of said returning means.

2. A display device comprising a frame, having a series of openings therein, placards held in displayed position behind said openings, box-like receptacles in said frame, guide rails disposed vertically in said frame, carriers adapted to ride on said rails, means for keeping said carriers in fixed spaced relation, means for moving said carriers, and means on said carriers for removing said placards from display position and depositing the same in said receptacles, and an inclined bottom in said receptacles for properly positioning said placards.

3. A display device comprising a frame, supports and receptacles in said frame, a series of placards having their ends associated with said supports, said supports being so inclined that the placard ends will move by gravity towards the lower ends of said supports, and means for moving the placards from position on some of said supports and depositing them in said receptacles, and an inclined bottom in said receptacles for allowing said placards to assume the proper position on other of said supports.

4. A display device comprising a frame, receptacles in said frame, rails in said frame for holding a plurality of placards to be displayed, rails for holding the displayed placards adjacent said receptacles, means for moving said placards from the display rails to the receptacles, and inclined bottoms in said receptacles for causing said placards to fall to a position to engage the rails adjacent said receptacles.

JOHANNES DINGDAHL.
